DRILLING MACHINE

Louis J. Fellay, Peoria, Ill., assignor to Dooley Bros., Peoria, Ill., a corporation of Illinois

Application June 23, 1934, Serial No. 732,881

16 Claims. (Cl. 255—46)

This invention has reference to drilling machines and although not limited in its application is preferably adaptable to machines of the coal and rock drilling type.

5 The invention has for its principal object to provide a safety clutch means operable under certain drilling operations whereby to control the actuation of the thread or feed bar, which carries in association therewith the usual auger or 10 drilling tool.

The invention has for a further object an improved liner or feed-nut assembly, operable in 15 association with said clutch means, which effects the forward feeding and retraction of the thread or feed bar through said drilling machine toward and away from the material being worked upon.

A further object of the invention is to completely house or enclose said clutch means and 20 said liner assembly, so that the operating elements thereof are out of reach and out of contact with the clothing and body of an attending workman, thereby making the machine and the attendants to its drilling operations a safe one.

25 The invention has for a still further object to provide a manually controllable lever or operating means located on the exterior of said housing and connected with said clutch means and said liner assembly adapted for movement by an attendant to one position, whereby to cause the liners of said assembly to have threaded engagement with a rotative thread or feed bar and simultaneously actuating said clutch means to cause said liner assembly to be non-rotative with 30 said thread or feed bar, and further to enable said thread or feed bar to be rotatively fed through said non-rotative liner assembly and said machine; said lever or operating means movable to an intermediate position, whereby the liners of said assembly retain their threaded engagement with said rotative thread or feed bar, and simultaneously actuating said clutch means to cause said liner assembly to become rotative with 35 said thread or feed bar, thereby stopping the feeding movement of said bar through said liner assembly and said machine; and said lever or operating means movable to another position, whereby the liners of said assembly are caused to be separated and disengaged from said rotative 40 thread or feed bar and non-rotative therewith, whereby to permit a manual selective positioning of said thread or feed bar with respect to a new drilling operation, that is, the thread or feed bar in this position of the lever or operating means 45 may be manually pulled or pushed by an at-

tendant through the separated liners of the assembly to assume a new or selective positioning of said bar when not desiring to accomplish such positioning by means of the liner assembly having the thread or feed bar fed therethrough in a 5 forward or backward rotative movement.

Other and further objects will more fully appear from the following description.

That the invention may be more fully understood, reference is had to the accompanying drawings forming a part of this description and illustrating a preferred embodiment of the invention, 10 in which:

Fig. 1 is a fragmentary plan view of my improved drilling machine incorporating my invention, the manually controllable lever or operating means, shown in full lines, and illustrating in 15 dotted lines other operating positions thereof;

Fig. 2 is a partial sectional view in elevation as the same would appear if taken on the line 20 2—2, Fig. 1, the clutch means and liner assembly thereof illustrated in the position they would assume when the manually controllable lever or operating means, shown in full lines, in Fig. 1, is moved to the right hand dotted line position, 25 shown in said figure;

Fig. 3 is a view somewhat similar to Fig. 2 illustrating the clutch means and liner assembly in the positions they would assume with the 30 manually controllable lever or operating means in the full line position, as it is shown in Fig. 1;

Fig. 4 is a view similar to Figs. 2 and 3, showing the clutch means and liner assembly in the 35 positions they would assume when the manually controllable lever or operating means is moved from the full line position, as shown in Fig. 1 and detailed in Fig. 3, to the left hand dotted line position, as illustrated in Fig. 1;

Fig. 5 is a sectional view in elevation, looking in the direction of the arrows, as the same would 40 appear if taken on the line 5—5, Fig. 4, said figures illustrating the liners of the liner assembly separated or disengaged from the thread or feed bar;

Fig. 6 is a partial sectional view in elevation, 45 looking in the direction of the arrows, as the same would appear if taken on the line 6—6 of Fig. 1 and if taken on the line 6—6 of Fig. 3;

Fig. 7 is a sectional view in elevation showing 50 certain of the clutch elements, looking in the direction of the arrows, as the same would appear if taken on the line 7—7 of Fig. 2, the main gear housing of said drilling machine being illustrated in full lines and partly broken away;

Fig. 8 is a plan view of the so-called liner as- 55

sembly comprising the liner cage with its plain and spline hub ends, showing one of the interiorly threaded liner members and the liner shifter ring encircling said liner cage in section;

5 Fig. 9 is a sectional view in elevation of the driving gear hub and thread or feed bar, looking in the direction of the arrows, as the same would appear if taken on the line 9-9, Fig. 2;

10 Fig. 10 is a side view in elevation, partly broken away, of the dental clutch forming a part of said clutch mechanism of said machine;

15 Fig. 11 is a bottom plan view of the shifter clutch engagement member, which cooperates with the dental clutch illustrated in Fig. 10, the circular-like finger portions thereof which cooperate with the shifter ring illustrated in section in Figs. 2, 3, 4 and 8, being broken away, said circular-like finger portions shown in full section in Fig. 6;

20 Fig. 12 is a fragmentary view, illustrating in side elevation, one end of the liner members, shown in assembled or juxtaposed position, and

Fig. 13 is an end view in elevation of the liner members illustrated in Fig. 12.

25 Like characters of reference denote corresponding parts throughout the figures.

Referring to the drawings, particularly Fig. 1, 1 designates the thread or feed bar main housing upon one side of which is provided a turn-table support member 2 which is adapted to cooperate with a similar turn-table support member on a drill post, not shown, for supporting and permitting swivel movement of the drilling machine when mounted for drilling operations. A motor mounting lug or support 3 is provided on said housing 1 preferably opposite said member 2 having an opening 4 therein for the securement and adjustment of preferably an electric reversible motor, not shown. On the inner end of said

30 main housing 1 is provided a gear housing 5 comprising a main body portion A and an off-set portion B, said portions A and B enclosing meshed gears, not shown. The driving gear in the off-set portion B is adapted to be connected by suitable shafting, not shown, to the motor, not shown, for imparting rotative movement to said gears and thereby rotate the thread or feed bar C in a manner to be described.

35

The hub end of the thread or feed bar driving gear 6 which is disposed within the main body portion A of the gear housing 5 is best seen in Figs. 2 and 9, although illustrated in Figs. 3 and 4. The thread or feed bar C is not unlike in construction the usual feed bar in drilling machines of this type, and is threaded throughout its length and is provided with oppositely disposed grooves 7 extending preferably throughout its length into which are adapted to be received the interiorly disposed driving lugs 8 of the gear 6 which, when the gear 6 is rotated will impart rotation to the bar C, as will be understood.

40 A liner housing 9 is suitably connected to the inner end of the main body portion A of the gear housing 5 to which is suitably connected at its forward end a preferably split tube support 10 into which is preferably frictionally held an elongated protecting tube or sleeve 11 which functions as a guard and protection against the body or clothing of an attending workman coming into contact with the bar C when rotating and causing possible injury.

45 Disposed within an annular shoulder of the main body portion A of the gear housing 5 is an outer race 12 of a roller bearing assembly, the inner race 13 thereof providing a bearing

5 support for the hub end of a dental clutch member 14 seen in Figs. 2, 3, 4 and 7 and shown in detail in Fig. 10, said member being provided on the periphery thereof with a plurality of clutch teeth 15. The hub end of said dental clutch member 14 is in axial alignment with the hub end of the driving gear 6 and abuts the same. The main body portion of the clutch member 14 is somewhat off-set to the hub portion thereof to provide an inner well portion, as disclosed, 10 the inner annular wall of said off-set portion being provided with a plurality of recesses for the reception of the spline-fitted hub end 16 of a liner cage 17, said cage illustrated in detail in Fig. 8. The end wall 18 of the cage 17 preferably abuts the outer end face of the off-set portion of the dental clutch member 14, as shown. The hub ends 16 and 19 of the liner cage 17 are likewise in axial alignment with the hubs of the members 14 and 6, through which, including the 20 housing 1, is adapted to be received the thread or feed bar C.

25 The opposite end hub 19 of the liner cage 17 is smooth faced and is received within the tube support 10 and has a bearing relation with a bearing member 20 provided therein. The companion end wall 21 of the cage 17 likewise preferably abuts the bearing member 20. The end walls 18 and 21 of the cage 17 are connected together by two oppositely disposed and relatively thin side walls 22, 22, the height thereof being preferably considerably less than the height of the end walls, as indicated in elevation, see Figs. 2, 3 and 4. The inner faces of said side walls are flat and the outer faces thereof are rounded in contour to conform to the peripheries of the end walls 18 and 21, see Figs. 5, 6 and 8.

30 Adapted to be operatively disposed and carried within said cage 17 is a pair of separable threaded like-formed liner members 23, 23 and the description of one will suffice for the other. The ends of the liners are provided with upstanding end walls 24, 24, the outside faces of which are preferably smooth to facilitate their movement within the cage 17 when assembling and separating the liners for certain drilling operations, to be described. On the outside of each liner and extending substantially throughout the length thereof is a centrally disposed cam-like 35 member 25. Said member, see Figs. 2, 3, 4 and 8, near one end, provides a flat riding surface 25 which extends downwardly as at 27 to the body of the liner to provide a further flat portion 28 which meets forwardly with an upstanding and somewhat taller flat portion 29 than the surface 26, said portion 29 forming with its connection with the portion 28 a V like wedge as at 30, said inclined face or jaw of the portion 29 designated 40 31. The underside or inner surfaces of the half section liners are screw threaded to fit the screw threads of the feed bar C. Portions of the length of each of the meeting faces of said liners are serrated as at 32 so that when the liners are assembled in closed bar feeding position about the feed bar C, the liners will be guided into proper threaded engagement with the feed bar C and be prevented from wobbling and thereby maintain the liners in proper alignment with respect thereto. The liners are illustrated in assembled position in Figs. 12 and 13 and shown within the cage 17 in Fig. 8.

45 A liner shifter ring 33 is adapted to have a sliding fit with the rounded outer faces of the side walls 22, 22 of the cage 17, see Fig. 8, and to also 50

have a sliding fit relation with the flat riding surface 26 of the web 25 of the liners 23, 23 when they are in a closed or assembled position about the feed bar C, as shown in Fig. 2.

Referring to Figs. 1, 2, 3, 4 and 6, the liner housing 9 pivotally supports an operating handle or lever arm 34 at 35, said handle having a slot or opening therein in which is slidably mounted a pin 36 which extends down through and is slidably arranged in an elongated slot or opening in the housing 9 to which pin is suitably connected an elongated shifter member 37 which is adapted to be actuated in and lengthwise of said housing 9 by said handle or arm 34, the ends of said shifter member being received in their extended positions in slots 38, 38 in the housings 5 and 10, respectively. At the connection of said shifter member 37 to said pin 36, there is provided a yoke-like member comprising downwardly curved arms 39, 39, see Fig. 6, which are adapted to be received in an annular groove or recess 40 provided in said shifter ring 33, whereby when the shifter member 37 is actuated lengthwise of the housing 9 by means of the handle or arm 34, the shifter ring 33 will be likewise actuated with said shifter member 37.

Rearwardly the connection of said yoke members 39, 39 to said shifter member 37, and on the underneath side thereof, there is provided a depending engagement member 41 thereon adapted to cooperate with the teeth 15 of the dental clutch 14. The forward face of the shifter ring 33 is beveled as at 42 to cooperate with the diagonal jaw faces 31 of the liners, for purposes to be described.

Assuming the forward end of the thread or feed bar C, which is protected by the sleeve 11, is in position for a drilling operation, the operator or attendant will move the handle or arm 34 to the right hand dotted line position shown in Fig. 1 which is that position shown in detail in Fig. 2. The operator will next start the motor, not shown, which will impart rotative movement to the gears within the portions A and B of the housing 5, thereby rotating the driving gear hub 6 and the thread or feed bar C. With the handle 34 in the position shown in Fig. 2, the shifter ring 33 has caused the threaded liners 23, 23 within the cage 17 to move toward the feed bar C and become threadedly associated therewith whereby to act as a nut and cause the thread or feed bar C to be rotatively fed forward toward the work to be drilled. Simultaneous with the movement of said handle 34 to the position just described, including the yoke-like members 39, 39 and shifter ring 33, the engagement member 41 of the shifter member 37 will be caused to have an immediate clutch engagement with the teeth 15 of the dental clutch 14, thereby making stationary and preventing rotative movement of said dental clutch member 14, the cage 17 by reason of the spline fitting connection 16 with said dental clutch member 14, and the assembled liners 23, 23 within said cage 17. In other words, with the parts in the position illustrated in Fig. 2, the thread or feed bar C is fed rotatively forward through the stationary assembled liners 23, 23 as long as the motor, not shown, is operated. In most drilling machines, the driving motors are reversible. In the event the motor is reversed with the parts in the position as shown in Fig. 2, it will be understood that the extended thread or feed bar C will be caused to be rotatively fed backwardly without any disturbance of the position of the handle 34, as it is shown in Fig. 2.

With the movement of the handle or lever arm

34 to the full line position, shown in Fig. 1, the parts assume the position as shown in detail in Figs. 3 and 6. In this position of the handle 34, the forward feeding movement of the thread or feed bar C is stopped, however, the rotative movement of such feed bar C continues with the operation of the driving motor, not shown. It often occurs in drilling operations where it is desirable to clean out the drilled hole by means of stopping the forward feeding movement of the feed bar and either continuing the rotation of the feed bar or reversing such rotation of the feed bar within the hole, which will throw out or feed back any collected drillings, dirt, etc., within the hole.

Referring now particularly to Fig. 3 it will be observed that the shifter ring 33 has been advanced along the flat riding surface 26 of the cam-like member 25 of the liners 23, 23 but with said liners still retaining their assembled and threaded engagement with the thread or feed bar C. Simultaneous with the movement of said shifter ring 33 by means of the lever 34 and yoke-like members 39, 39, the movement of said shifter member 37 with said shifter ring 33 will cause the engagement member 41 to declutch with the teeth 15 of the dental clutch 14, thereby permitting the members comprising the dental clutch 14, the cage 17 with its spline hub end 16 interfitting the clutch 14, and the assembled liners 23, 23 within said cage 17 to rotate with the rotating thread or feed bar C. In view of the cage 17 and the assembled liners 23, 23 therewithin in threaded engagement with said feed bar, now free and capable of rotating with said rotating feed bar, it is obvious that no forward feeding or backward movement, in the event of the reversing of the motor, will be transmitted to said bar.

With the movement of the handle or lever arm 34 to the left hand dotted line position shown in Fig. 1, the parts assume the position as shown in detail in Figs. 4 and 5. In this position of the handle 34, assuming that the driving motor, not shown, is running and the hub end of the driving gear 6 is imparting rotation to the thread or feed bar C, the liners 23, 23 are disengaged with said feed bar, therefore, no feeding movement is imparted to said bar. The main purpose of providing this adjustment or position of the handle 34 or lever arm 34 is to enable the manual adjusting or positioning of the thread or feed bar C with respect to the work to be drilled. In such case, the driving motor, not shown, is stopped and it will be understood that with the stopping of said motor the thread or feed bar C will discontinue its rotative action therewith, thereby permitting the operator or attending workman to grasp the free protruding rear end of said bar and either push or pull it through the disassembled liners 23, 23 to the desired position, whereupon, depending upon the instant drilling conditions, the operator will throw the lever 34 to either the full line position, as shown in Fig. 1, which position is shown in Fig. 3, or to the right hand dotted line position, as shown in Fig. 1, which position is shown in Fig. 2 and the driving motor, not shown, is again started to effect a forward feeding rotative action or a reverse rotative action of the feed bar C, as may be desired.

Referring now particularly to Fig. 4, the movement of the lever 34 to such left hand dotted line position as shown in Fig. 1, has caused the shifter ring 33 to advance along the flat riding surface 26 of the cam-like member 25 of the

5

65

70

75

liners 23, 23 until the beveled face 42 of said shifter ring contacts the diagonal jaw faces 31 of said liners, whereupon in the further advancing movement of said shifter ring 33 to the 5 position illustrated in Fig. 4, the faces 31 of said liners ride upwardly upon the beveled face 42 of the shifter ring 33 resulting in the liners becoming separated and disengaged from their threaded engagement with the thread or feed 10 bar C and so held in said separated position until the lever 34 is moved to one or the other of said 15 previously described positions.

It will be understood that upon moving the 15 lever 34 from the position shown in Fig. 4 to the position shown in Fig. 3, that the rearward resultant movement of the shifter ring 33 will cause the rear beveled wall of said ring to engage the 20 sloping faces 27 of said liners 23, 23, thereby depressing said liners, whereupon said ring will ride upon the flat riding surfaces 26 of said liners, as illustrated in Figs. 3 and 6, causing the liners 25 23, 23 to be closed and assembled upon and have threaded engagement with the thread or feed bar C.

25 Referring to Figs. 1 and 6, the liner housing 9 and the handle or lever arm 34 are provided with cooperating detent elements, whereby in any of the three adjusted positions of said lever, as 30 shown and described, said lever will be substantially fixed and be prevented from jarring or vibrating and causing accidental displacement of said lever from said fixed positions.

What I claim is:

1. In a drilling machine, in combination, a 25 housing providing a closure, a cage within the housing, a thread-bar operable through said housing and said cage, coacting separable liner sections disposed within said cage and threaded for engagement with the thread-bar, operating means 40 for the thread-bar, and means for moving the liner sections within said cage to operative and inoperative positions with respect to the thread-bar.

2. In a drilling machine, in combination, a 45 housing providing a closure, a cage within the housing, a thread-bar operable through said housing and said cage, coacting separable liner sections confined within said cage and threaded for engagement with the thread-bar, operating means for the thread-bar, a shifter member associated 50 with said liners, manually adjustable means movable to selective positions and having a connection with said shifter member, in one of which positions, said member is actuated causing the liners to function as a nut for axial movement of the 55 thread-bar, in another of which positions, said member is actuated causing the liners to be held for rotation with the thread-bar and in a third position, said member is actuated causing the liners to separate out of operation with the 60 thread-bar.

3. In a drilling machine, in combination, a 65 housing providing a closure, a cage within the housing, a thread-bar operable through said housing and said cage, coacting separable liner sections confined within said cage and threaded for engagement with the thread-bar, operating means 70 for the thread-bar, a shifter member associated with said liners, manually adjustable means movable to selective positions and having a connection with said shifter member, in one of which positions, said member is actuated causing the liners to function as a nut for axial movement of the thread-bar, in another of which positions, said member is actuated causing the liners to 75 be held for rotation with the thread-bar and in a

third position, said member is actuated causing the liners to separate out of operation with the thread-bar, and means for fixedly positioning said adjustable means.

4. In a drilling machine, in combination, a 5 housing, a thread-bar rotatively operable through said housing, a cage rotatively disposed within the housing, coacting separable liner sections confined within said cage and interiorly threaded for engagement with the thread-bar, operating means 10 for the thread-bar, a clutch member associated with said cage, a liner shifter member associated with said liners and said cage, manually controllable means for the clutch member and shifter member movable to selective positions, in one of 15 which, said controllable means prevents the rotation of said clutch member and said cage and the shifter member actuates the liners within said cage to function as a nut for axial movement of the thread-bar, in another of which, 20 said controllable means permits the rotation of said clutch member and said cage and liner sections, said shifter member holding the assembled liner sections for rotation with the thread-bar and in a third position, said controllable 25 means causes the shifter member to actuate the liner sections within said cage whereby said liners disengage out of operation with the thread-bar.

5. In a drilling machine, in combination, a 30 housing, a thread-bar rotatively operable through said housing, a cage rotatively disposed within the housing, coacting separable liner sections confined within said cage and interiorly threaded for engagement with the thread-bar, operating means 35 for the thread-bar, a clutch member associated with said cage, a liner shifter member associated with said liners and said cage, manually controllable means for the clutch member and shifter member movable to selective positions, in one of which, said controllable 40 means prevents the rotation of said clutch member and said cage and the shifter member actuates the liners within said cage to function as a nut for axial movement of the thread-bar, in another of which, said controllable means permits the rotation of said clutch member and said 45 cage and liner sections, said shifter member holding the assembled liner sections for rotation with the thread-bar and in a third position, said controllable means causes the shifter member 50 to actuate the liner sections within said cage whereby said liners disengage out of operation with the thread-bar, and means for fixedly positioning said controllable means.

6. In a drilling machine, in combination, a 55 housing, a thread-bar operable through the housing, a cage within the housing, coacting separable liner sections disposed within said cage and interiorly threaded for engagement with the thread-bar, cam-like surfaces provided on the 60 exterior faces of said liner sections, operating means for the thread-bar, and means for coacting with the cam-like surfaces of said liner sections whereby to move the liner sections within said cage to operative and inoperative positions 65 with respect to the thread-bar.

7. In a drilling machine, in combination, a 70 housing, a thread-bar operable through the housing, a cage within the housing, coacting separable liner sections disposed within said cage and interiorly threaded for engagement with the thread-bar, cam-like surfaces provided on the exterior faces of said liner sections, a liner shifter member carried by said cage for coacting with 75 said cam-like surfaces, operating means for the

thread-bar, and a manually controllable means operable to move said shifter member whereby to actuate the liner sections within said cage to operative and inoperative positions with respect 5 to the thread-bar.

8. In a drilling machine, in combination, a housing, a thread-bar operable through the housing, a cage within the housing, coacting separable liner sections disposed within said cage and interiorly threaded for engagement with the thread-bar, cam-like surfaces provided on the exterior faces of said liner sections, a liner shifter member carried by said cage for coacting with said cam-like surfaces, operating means for the thread-bar, a manually controllable means operable to move said shifter member whereby to actuate the liner sections within said cage to operative and inoperative positions with respect to the thread-bar, and means for fixedly positioning said controllable means.

9. In a drilling machine, in combination, a housing, a thread-bar operable through the housing, coacting separable liner sections operable within said housing and interiorly threaded for engagement with the thread-bar, a plurality of cam-like surfaces provided on the exterior faces of said liner sections, a shifter member for coacting with said cam-like surfaces, operating means for the thread-bar, and a manually controllable means for the liners movable to selective positions, in one of which, to move the shifter member in coaction with certain of said cam-like surfaces of said liners whereby to actuate the liner sections within said housing to an operative position with respect to said thread-bar, and in another of which, to move the shifter member in coaction with certain other of said cam-like surfaces of said liners whereby to actuate the liner sections within said housing to an inoperative position with respect to said thread-bar.

10. In a drilling machine, in combination, a housing, a thread-bar operable through the housing, coacting separable liner sections operable within said housing and interiorly threaded for engagement with the thread-bar, a plurality of cam-like surfaces provided on the exterior faces of said liner sections, a shift member for coacting with said cam-like surfaces, operating means for the thread-bar, and a manually controllable means for the liners movable to selective positions, in one of which, to move the shifter member upon certain of said cam-like surfaces of said liners whereby to actuate the liner sections within said housing to an operative position with respect to said thread-bar, and in another of which, to move the shifter member upon certain other of said cam-like surfaces of said liners whereby to actuate the liner sections within said housing to an inoperative position with respect to said thread-bar, and means for fixedly positioning said controllable means.

11. In a drilling machine, in combination, a housing, a thread-bar operable through the housing, a cage within the housing, coacting separable liner sections disposed within said cage and interiorly threaded for engagement with the thread-bar, cam-like surfaces provided on the exterior faces of said liner sections, a liner shifter member carried by said cage for coacting with said cam-like surfaces, operating means for the thread-bar, and manually controllable means for the shifter member movable to selective positions, in one of which, said controllable means causes said shifter member to coact with said cam-like

surfaces of said liner sections and actuate said liner sections within said cage to function as a nut for axial movement of the thread-bar, in another of which, said controllable means permits the rotation of said cage and liner sections, said shifter member holding the assembled liner sections for rotation with the thread-bar and in a third position, said controllable means causes said shifter member to coact with said cam-like surfaces of said liner sections whereby to actuate the liner sections within said cage to disengage out of operation with the thread-bar.

12. In a drilling machine, in combination, a housing, a thread-bar operable through the housing, a cage within the housing, coacting separable liner sections disposed within said cage and interiorly threaded for engagement with the thread-bar, cam-like surfaces provided on the exterior faces of said liner sections, a liner shifter member carried by said cage for coacting with said cam-like surfaces, operating means for the thread-bar, and manually controllable means for the shifter member movable to selective positions, in one of which, said controllable means causes said shifter member to coact with said cam-like surfaces of said liner sections and actuate said liner sections within said cage to function as a nut for axial movement of the thread-bar, in another of which, said controllable means permits the rotation of said cage and liner sections, said shifter member holding the assembled liner sections for rotation with the thread-bar and in a third position, said controllable means causes said shifter member to coact with said cam-like surfaces of said liner sections whereby to actuate the liner sections within said cage to disengage out of operation with the thread-bar, and means for fixedly positioning said controllable means.

13. In a drilling machine, in combination, a housing, a thread-bar operable through the housing, coacting separable liner sections operable within said housing and interiorly threaded for engagement with the thread-bar, a plurality of cam-like surfaces provided on the exterior faces of said liner sections, a member for coacting with said cam-like surfaces, operating means for the thread-bar, and manually controllable means for the liner sections movable to selective positions, in one of which, to move said member in coaction with certain of said cam-like surfaces of said liner sections whereby to function as a nut for axial movement of the thread-bar, in another of which, said controllable means permits the rotation of said liner sections, said member holding the assembled liner sections for rotation with the thread-bar, and in a third position, to move said member in coaction with certain other of said cam-like surfaces of said liner sections whereby to actuate the liner sections within said housing to disengage out of operation with the thread-bar.

14. In a drilling machine, in combination, a housing, a thread-bar operable through the housing, coacting separable liner sections operable within said housing and interiorly threaded for engagement with the thread-bar, a plurality of cam-like surfaces provided on the exterior faces of said liner sections, a member for coacting with said cam-like surfaces, operating means for the thread-bar, manually controllable means for the liner sections movable to selective positions, in one of which, to move said member in coaction with certain of said cam-like surfaces of said inner sections whereby to function as a nut for axial

- movement of the thread-bar, in another of which, said controllable means permits the rotation of said liner sections, said member holding the assembled liner sections for rotation with the 5 thread-bar, and in a third position, to move said member in coaction with certain other of said cam-like surfaces of said liner sections whereby to actuate the liner sections within said housing to disengage out of operation with the thread-bar, 10 and means for fixedly positioning said controllable means.
15. In a drilling machine, in combination, a housing, a thread-bar operable through the housing, coacting separable liner sections operable 15 within said housing and interiorly threaded for engagement with the thread-bar, operating means for the thread-bar, mechanism embracing said liners adapted for coaction therewith, and manually controllable means for the liner sections 20 movable to selective positions, in one of which, to move said mechanism in coaction with the liner sections whereby said sections are moved in assembled threaded relation with the thread-bar to function as a nut for axial movement of the thread-bar through the housing, in another of which, said mechanism is operated to coact with the assembled liner sections whereby said sections are held 25 for rotation with the thread-bar, and in which, said mechanism is operated to coact with the assembled liner sections whereby said sections are held for rotation with the thread-bar, and in

a third position, said mechanism is operated to coact with said liners whereby to disassemble said liner sections out of engagement with the thread-bar.

16. In a drilling machine, in combination, a 5 housing, a thread-bar operable through the housing, coacting separable liner sections operable within said housing and interiorly threaded for engagement with the thread-bar, operating means for the thread-bar, mechanism embracing said 10 liners adapted for coaction therewith, manually controllable means for the liner sections movable to selective positions, in one of which, to move said mechanism in coaction with the liner sections whereby said sections are moved in assembled 15 threaded relation with the thread-bar to function as a nut for axial movement of the thread-bar through the housing, in another of which, said mechanism is operated to coact with the assembled liner sections whereby said sections are held 20 for rotation with the thread-bar, and in a third position, said mechanism is operated to coact with said liners whereby to disassemble said liner sections out of engagement with the thread-bar, and means for fixedly positioning said controllable 25 means.

LOUIS J. FELLAY.
